UNITED STATES PATENT OFFICE.

HARRY M. ACLY, OF PITTSFIELD, MASSACHUSETTS, ASSIGNOR TO STANLEY ELECTRIC MANUFACTURING COMPANY, OF PITTSFIELD, MASSACHUSETTS, A CORPORATION OF NEW JERSEY.

LOCKING AND TRIPPING DEVICE FOR SWITCHES.

No. 823,984.

Specification of Letters Patent.

Patented June 19, 1902.

Application filed November 17, 1904. Serial No. 233,082.

To all whom it may concern:

Be it known that I, HARRY M. ACLY, a citizen of the United States, residing at Pittsfield, county of Berkshire, State of Massachusetts, have invented certain new and useful Improvements in Locking and Tripping Devices for Switches, of which the following is a specification.

My invention relates to automatic switches or breakers for electric circuits; and its object is to provide a novel form of locking and tripping devices for such switches, which is exceedingly simple in construction and reliable in action.

My invention will best be understood by reference to the accompanying drawings, in which—

Figure 1 shows a side elevation of a circuit-breaker provided with a tripping device arranged in accordance with my invention. Fig. 2 shows a similar view of the circuit-breaker at the instant of opening, and Figs. 3 and 4 show detailed views of the locking device.

In the drawings, A represents the operating-handle by means of which the switch is closed. This handle is pivoted to the outer end of the links B, the inner end of which is pivoted at b to the switch-support. Handle A is also pivotally connected to the contact-carrying member C, one end of which is also pivoted at c to the support. The member C is provided with a stop c', of yielding material, such as rubber, adapted to be engaged by the handle A to limit the movement of the switch when opened, as shown in Fig. 2. Secured to the member C is the switch-contact D, which I have shown as of the usual form of laminated brush supplied with auxiliary contacts d d' to receive the arc when the switch is opened. The specific form of manual operating mechanism for closing the switch and the specific form of switch-contacts form no part of my invention, which is applicable to switches of any well-known construction.

Secured to the member D by the link E is the rod F, longitudinally movable in the guide G and normally pressed outward by the compression-spring H. This spring thus tends at all times to open the switch. The guide G is formed with a sloping ridge I beneath the rod F, and between the ridge I

and the rod F is placed a roller J. The rod F is preferably square, as shown, or formed with a flattened bearing-surface for the roller. The roller J is at all times pressed forward into the position shown by the follower K and its actuating compression-spring k, as is clearly shown in Fig. 3. Thus when the switch is closed by pushing handle A inward into the position shown in Fig. 1 the roller J is maintained in the position shown in engagement with both rod F and the inclined ridge during the inward movement of the rod F. When the switch is closed and the handle A is released, the pressure of compression-spring H tends to move rod F outwardly to open the switch, and its tendency to movement only locks the roller J more firmly in position, so as to wedge the rod F firmly between the roller and the upper portion of the guide G. The switch is thus held closed against the pressure of spring H.

L represents a toggle-lever, one end of which loosely engages the roller J by a pin-and-slot connection. The central portion of the toggle L rests upon a pin l, which is supported in guide G, as shown, directly above the tripping-magnet M. The core m of the tripping-magnet is normally held in the position shown in Fig. 1 by a spring m' or by gravity, or both. When the predetermined amount of current flows through tripping-magnet M, the core m will be drawn up, striking the pin l and moving the toggle-lever L, as shown in Fig. 2. The roller J is thus forced backward momentarily, compressing the spring k and releasing the rod F. The switch is consequently free to open under the pressure of the mainspring H.

I have shown the core m provided with a tripping-lever N extending through the switch-support, so that the switch can be readily tripped by hand.

I do not desire to limit myself to the particular construction and arrangement of parts here shown, but aim in the appended claims to cover all modifications which are within the scope of my invention.

What I claim as new, and desire to secure by Letters Patent of the United States, is—

1. In a locking and tripping device, in combination with a movable member and means tending to move said member, an independ-

ently-movable locking-piece adapted to lock said member by frictional engagement therewith, said member and locking-piece being so arranged that the pressure of said moving means on said member produces said engagement, an electromagnet, and operative connections between said magnet and said locking-piece whereby said locking-piece is moved from locking position.

bers, and an electromagnet acting upon said toggle-joint.

6. In combination, a switch member, a longitudinally-reciprocating rod secured thereto, a spring tending to open said switch, a surface inclined to said rod, a friction-roller mounted between said rod and said surface, the tendency to movement of said rod under the pressure of said spring being in a direction to wedge said roller between said rod and inclined surface, an electromagnet, and operative connections between said roller and said magnet. 55 60 65

7. In combination, a switch member, a longitudinally-reciprocating rod secured thereto, a spring tending to open said switch, a surface inclined to said rod; a friction-roller mounted between said rod and said surface, the tendency to movement of said rod under the pressure of said spring being in a direction to wedge said roller between said rod and inclined surface, a spring-pressed follower normally maintaining said roller in engagement with said rod and said inclined surface, an electromagnet, and operative connections between said electromagnet and said roller. 75

8. In combination, a switch member, a longitudinally-reciprocating rod secured thereto, a spring tending to open said switch, a surface inclined to said rod, a friction-roller mounted between said rod and said surface, the tendency to movement of said rod under the pressure of said spring being in a direction to wedge said roller between said rod and inclined surface, a toggle-joint loosely engaging said roller, and an electromagnet acting upon said toggle-joint. 85

9. In a locking and tripping device, in combination with a longitudinally-movable rod and a spring tending to move said rod, a guide bearing against one surface of said rod, a friction-roller bearing against the opposite surface of said rod, a surface inclined to said rod and adapted to support said roller, and an electromagnet operatively connected to said roller. 95

In witness whereof I have hereunto set my
hand this 15th day of November, 1904.
HARRY M. ALVY

10 2. In a locking and tripping device, in combination with a movable member and means tending to move said member, an independently-movable locking-piece frictionally engaging said member and adapted to be
15 moved by the movement of said member to bind said member in position, and electromagnetic means for releasing the locking-piece.

3. In a locking and tripping device, in combination with a movable member and means tending to move said member, an independently-movable locking-piece engaging said member and adapted to be moved by the movement of said member to bind said member in position by frictional engagement, and electromagnetic means for releasing the locking-piece.

4. In a locking and tripping device, in combination with a movable member and means tending to move said member, a surface inclined to said member, a friction-roller arranged between said member and said surface, means for holding said roller normally in contact with said member and said surface, the tendency of said member to move under the pressure of said moving means being in a direction to increase the pressure on said roller, an electromagnet, and operative connections between said magnet and said roller.

45 5. In a locking and tripping device, in combination with a movable member and means tending to move said member, a surface inclined to said member, a friction-roller ar-
45 ranged between said member and said surface, means for holding said roller normally in contact with said member and said surface, the tendency of said member to move under the pressure of said moving means be-
50 ing in a direction to increase the pressure on said roller, a toggle-joint adapted to move said roller out of engagement with said mem-
